HOSE STORAGE DEVICE

Frank P. Zierden, Cudahy, Wis.

Application May 13, 1947, Serial No. 747,629.

9 Claims. (Cl. 299—77)

1

This invention relates to improvements in means for storing hose within and particularly in space ordinarily wasted or little used space within the structural portions of a building while retaining ready access to the hose from exteriorly of the building or the storage space.

It is one object of the invention to provide means which may be merely added to a present building to provide for storage of hose within the building and in space not usually utilized while keeping the hose and the control valve therefor accessible from outside of the storage space.

Another object of the invention is to provide for the storage of a hose within a space of which the length of the hose is a multiple of more than two times the length of the space.

Another object of the invention is to provide for the storage of hose in a space within or closely adjacent to a building structural portion and to provide for invariable placing of the hose in one or more loops, free from interference between the looped portions, either during storage of the hose or while withdrawing the hose from the storage space.

A further object of the invention is to provide an outlet through a wall of a building for hose to be stored within the building wall or within or adjacent to a structural building portion, whereby the hose is kept continuously accessible from outside of the building wall or other structural portion of the building.

And a further object of the present invention is to provide an outlet through a building wall, or other structural portion such as a floor, for hose to be stored within such wall or floor and in which the structure of the outlet itself is such as to prevent movement of the nozzle end of the hose and of the means for controlling the supply valve into positions inaccessible from the free end of the outlet.

Objects and advantages other than those above set forth will be apparent from the following description when read in connection with the accompanying drawing, in which:

Fig. 1 is a view partially in section and partially in elevation showing the present invention applied to fragments of a building floor and wall.

Fig. 2 is a fragment of Fig. 1, on an enlarged scale;

Fig. 3 is an end view of an outlet box for insertion in a structural portion of a building;

Fig. 4 is a partial sectional view on the plane of line IV—IV of Fig. 2;

Fig. 5 is a cross sectional view showing the manner in which hose lies on the storage space floor and shelf;

2

Fig. 6 is a side elevation of a modified form of the present invention;

Fig. 7 is a vertical sectional view longitudinally of Fig. 6; and

Fig. 8 is a vertical section taken on the plane of line VIII—VIII of Fig. 7.

Generally, the storage space used is in a space between the floor joists, or within or immediately adjacent to a wall of a building, or within or immediately adjacent to other building structural portions, and providing a space clear of building structural elements and not utilized for other purposes. In one modification of the invention such space is enclosed, preferably with sheet metal, for some distance from the wall of the building, and may be provided with a shelf, also preferably of sheet metal, spaced closely above the enclosing sheet but with one end of the shelf a considerable distance from the building wall and with such end sloping toward the enclosing sheet to substantially only the thickness of the hose above the enclosing sheet. An opening through the building wall from the enclosed space is provided with an outlet including a casing through which both a hose and a rod for the water-controlling valve extend by way of separate passages. The casing is joined with an outlet box to be set on or in the building wall and encloses both rollers, for guiding hose movement into and out of the casing, and the handle end of the valve control rod.

Referring particularly to the drawings, 12 and 13 represent structural elements of a building, such as the floor joists between which a clear space, preferably at least twenty-five feet in length, is available. A connection 14, with a source of water under pressure, is brought into the space and is provided with a valve 15 preferably turned so that the valve stem extends toward the building wall, generally designated 17. The water connection and the valve are preferably brought into the storage space adjacent the wall of the building. The space between the joists is enclosed by a smooth floor 19, preferably of sheet metal, provided with a door 20 for access to the water connection and the valve.

A shelf 23 may be placed between the building elements 12 and 13 at a distance above the space floor 19 only slightly greater than the diameter or thickness of a hose 24 which is to be connected with the valve 15. Such shelf is also preferably made of sheet metal, but, in any case, is smooth and without projections on either the upper surface or the under surfaces which might interfere with movement of the hose in the enclosed space. The end 25 of the shelf, which is

adjacent to the building wall 17, terminates at a considerable distance from such wall and is sloped toward the space door 19 to just clear a hose lying on the floor. If desired, both the space door and the shelf may be slotted or perforated for the drainage of moisture and to prevent the accumulation of dust or dirt therein.

An outlet with a casing portion, generally designated 30, and a box portion, generally designated 31, are placed with the casing portion extending through the wall 17 and with the box portion secured on the exterior of the wall or set into the wall, the box being made the dimensions of two bricks to facilitate setting the box into a brick or other masonry building wall. The casing portion 30 is formed from an outer casing tube 34 in which is eccentrically mounted an inner casing tube substantially divided into portions 35 and 36 by a ridge 37 pressed into the tube. Tube 35-36 is of such size as to pass hose 24 freely therethrough and to receive hose nozzle 38 until inward movement thereof is limited by the tube ridge 37. It will be seen that the tube 35-37 is so placed in the outer casing 34 as to be in the lower portion of the casing when the outlet is in use.

A rod comprising a first section 40, a second section 41, a third section 42 and a handle section 43 extends through the space between the outer casing 34 and the tube 35-37, and is guided in part by passing through a hole in an end plate 46 for the casing tube portion 34. The rod section 40 is forked at one end for connection with the valve hand-wheel 47 and extends into tubular second rod section 41 to provide a telescoping portion for ready connection with the valve. Such second rod section ends in a clevis-like structure joined with a similar structure on third rod section 42 to provide a joint 48 permitting universal movement between the second and third rod sections. The third rod section 42 is slotted to receive a lug 49 on one end of the rod handle section 43 for sliding to form a second telescoping portion of the rod, the other end of the rod section 43 being provided with a handle 50. The outlet box 31 is permanently joined with the casing 34 and closes one end of such casing except for an opening for one end of the nozzle or inner tube 35-37 and an opening through which the rod section 42 extends. The rod section 42 is thus supported at both ends and may be rotated to turn hand-wheel 47 for opening or closing the valve 15. A washer 54 with an internally extending ear 55 is placed about the end of rod section 42 with the ear extending into the slot in the rod section to provide a stop for movement of the lug 49 on rod section 43. The end of the rod section 42 is then formed over the washer to hold the parts in assembled relation, thus also permitting relative movement of the rod section 42 and the rear wall 56 of the box 31.

A pair of brackets 60 extend from the box wall 56 adjacent the end of the nozzle tube 35-37 and, in conjunction with the bottom wall 61 of the box, support a pair of rollers 62 to guide movement of the hose into and out of the tube 35-37 and prevent rubbing of the hose on the edge of the tube end. It will be seen that the box 31 has a top wall 65 sloped for "keying" into the wall 17 by the use of mortar and has a lip extending outwardly from the surface of the wall 17, that the box and walls 66 are flanged inwardly as at 67 to provide stops for a door 68 and a flange coacting with the box top flange 75

for receiving a lug 69 to prevent unauthorized use of the hose.

Assuming that the free space between the joists 12, 13 is approximately twenty-five feet in length, a hose which is approximately fifty feet in length may be fastened to the valve 15 at one end while the other end of the hose is passed through the tube 35-37 to receive the nozzle 38. The hose may be pulled out of the tube 35-37 until no more slack remains and used exteriorly of the space (or of the building). Opening of the valve 15 is accomplished simply by sliding the rod section 43 relative to the rod section 42 for a convenient distance and then turning the entire rod by use of the handle 50. After the hose has been used as desired, the hose is returned to the space merely by pushing the hose back through the tube, which slides the bight 24a of the hose back into the space until the nozzle 38 seats on the tube ridge 37 whereupon the hose is positioned as indicated in Fig. 1. It will thus be seen that a length of hose approximately double the length of the space may be inserted within such space.

If a hundred foot length of hose is to be accommodated in a twenty-five foot space, the shelf 23 is placed as above described. Assuming that the entire connected hose has been used exteriorly of the storage space, and is to be returned thereto, the hose is merely pushed back until the first bight 24a (see Fig. 5) of the hose is against the back wall 21 for the space between the joists. Further pressure axially of the hose then forms a second bight 24b in the hose which slides over the sloping lip 25 of shelf 23 and slides on the shelf until the second such bight is stopped by the storage space rear wall 21. A length of hose four times the length of the space can hence be accommodated by use of the shelf 23. It has been found that the above action takes place invariably if the shelf is located and formed as above described, and that the present means for storing the hose for ready accessibility may be used with any hose of sufficient rigidity to slide on a smooth surface by pushing axially on the hose. The hose can of course also be used within the building itself by removal of the nozzle to permit the hose to be pulled back through the tube 35-37 and out of the space through the door 20. However, return of the hose to the storage space does not then follow automatically as above described.

In the present instance, the wall 17 is shown as an outside wall of a residence including a foundation 73 on which rests a sill composed of two timbers 74 to which the joists 12, 13 may be joined and with the space between the joists filled with masonry or concrete. A building floor 75 is laid on the joists as usual and the usual wall 76, with a surfacing 77 is erected on the sills. It will be understood that the space employed for storing the hose, in the above modification of the invention, may be in space not otherwise employed in any of the walls or other structural elements of a building. Thus an interior wall may be used to receive a fire hose and its connections or the hose may be stored in the building floor as shown while the outlet is set into the floor with the cover flush with the floor surface.

Referring now to the modified form of the invention as shown in Figs. 6 to 7 inclusive, the combined wall outlet casing 30 and outlet box 31 is mounted in the wall 17 as above described and enters a receptacle generally designated 80

which is suitably supported adjacent the building wall or foundation as from a building joist 12. Such receptacle may be made from three channel members 81 formed to define three edges of the receptacle to which are attached plates or sheets 82 and 83 forming the receptacle sides. The side plate 83 remote from the joist 12 is provided with a door 84 adjacent the upper end of such side for access to the receptacle if the open upper end thereto should be so mounted as to restrict access therethrough into the receptacle. It will be understood, of course, that the upper end of the receptacle may be closed if desired. The sides 82 and 83 of the receptacle, if made of sheet metal, are preferably stiffened by forming diagonal ribs therein or thereon.

The dimensions of the receptacle 80 are determined by the size of the hose 86 to be stored therein. The outer diameter of the hose when the hose is under the maximum fluid pressure, determines the width A—B (see Fig. 8) of the receptacle which is such that the hose is readily movable therein, whether or not under pressure, and whether of the stiff walled or collapsible wall type. For example, the usual garden hose is 1 $\frac{1}{2}$ " outer diameter, hence the receptacle width should be approximately 1 $\frac{3}{8}$ ". The length C—D (see Fig. 7) of the receptacle may vary from 4 to 5', again depending upon the type of hose used, the length being such that the hose may fold as shown in Fig. 7, into its natural bends. It will be seen that the hose has a "standing" length 87 attached to the valve 15 and, in its stored position, extending downwardly into the receptacle to the bottom thereof where the hose piles up in loops 88. The loops rest on each other with the central portion of each loop resting on the bottom of the receptacle or on the next lower loop, while the ends of the loops rest against the hose length 87 and against the end of the receptacle, respectively. The depth E—F (see Fig. 8) of the receptacle is determined by the total length of the hose to be stored and whether or not the loops of the hose are capable of supporting the weight of the superimposed loops of the hose without damage, when the hose is not under pressure. It has been found for example, that a hundred foot length of garden type hose may be readily stored in a receptacle approximately 5' in depth. It will be seen that the hose weight is distributed between the bottom and the ends of the receptacle and is partially supported by valve 15. Hence, a considerable length of hose may be stored without such accumulated weight on the lower loops as to be injurious to the hose.

It will be understood that the receptacle may also be set into an ordinary wall between the studding thereof, or may be hung on the inside surface of the wall or may be buried beneath the floor. If one wall of the building is sufficiently smooth to allow vertical movement of the hose thereon, the receptacle wall adjacent thereto, may be omitted thus reducing the cost and weight of the receptacle without material change in rigidity. The outlet may enter the receptacle as shown, may be set at an angle with the vertical at the end thereof, may enter the receptacle through a side wall and may be set at any desired angle to either the length or width of the receptacle or to both such dimensions.

Although but one embodiment of the present invention has been illustrated and described, it will be apparent to those skilled in the art that various changes and modifications may be made therein without departing from the spirit of the

invention or from the scope of the appended claims.

I claim:

1. In a device for storing a hose and its nozzle in a building and in readily accessible position from exteriorly of the building, a box-like enclosure within the building, a water connection within the building accessible from within the enclosure for attachment of one end of the hose thereto, a valve controlling the flow of water from the connection into the hose, a rod for manually operating the valve from outside the building, and an outlet from the enclosure and building, the outlet having passages for free movement of the hose therethrough and retaining the nozzle in predetermined position and for receiving the rod whereby both the nozzle and the rod are continuously accessible from outside of the building.
2. In a device for storing a hose and its nozzle within a building for ready accessibility from exteriorly of the building at all times, a box-like enclosure within the building for receiving and retaining the hose in loops, a valve water connection within the building for attachment of the hose thereto, an outlet comprising a box portion and two telescoped tubes forming a casing portion providing two separate passages, the inner tube providing a passage for free movement of the hose therethrough and having an inwardly extending peripheral ridge limiting only movement of the nozzle thereinto, and a rod extending through the passage defined by the inner and outer tubes of the casing portion and for operating the valve from outside of the building.
3. In a device for storing a hose within a building for ready availability at all times and from exteriorly of the building, a box-like enclosure within the building for receiving and retaining the hose in loops, a water connection within the building for attachment of the hose thereto, a valve controlling flow of water from the connection into the hose, an outlet comprising a box portion and a casing portion formed from two telescoped tubes and providing two separate passages through the outlet, and a telescopic rod extending through the one of the passages defined by the inner and outer casing tubes for operating the valve from outside of the building, the rod having one telescopic portion within the building beyond one end of the outlet casing portion and having another telescopic portion within the casing for extension beyond the other end of the outlet casing portion.
4. In a device for storing a hose within a building for ready availability at all times and from exteriorly of the building, a box-like enclosure within the building for receiving and retaining the hose in loops, a water connection within the building for attachment of the hose thereto, a valve controlling flow of water from the connection into the hose, an outlet comprising a box portion and a casing portion formed from two telescoped tubes and providing two separate passages through the outlet, and a universally jointed rod extending through one of the passages defined by the inner and outer casing tubes for operating the valve from outside of the building, the rod having one telescopic portion within the building beyond one end of the outlet casing portion and having another telescopic portion within the casing for extension beyond the other end of the outlet casing portion, the universal joints of the rod being within the building

and exteriorly of the outlet and the portion of the rod within the casing portion being supported for rotary motion only.

5. In a device for storing a hose within a building for ready accessibility from exteriorly of the building at all times, a box-like enclosure within the building for receiving and retaining the hose in loops, a valved water connection within the building for attachment of the hose thereto, an outlet comprising a box portion and a casing portion defining a plurality of passages, one passage being adapted for movement of the hose therethrough and for retaining the hose nozzle in predetermined position, and a rod extending through another outlet passage 15 for operating the valve from outside the building, the box portion being adapted for insertion in the building wall and being open to the exterior of the building, the box portion having a lip extending from one side of the box for diverting water draining downwardly on the building wall from above the box, and having inwardly flanged box ends and a flanged hinged cover abutting the end flanges and with the cover flange coming below the box lip upon movement of the cover into box-closing position.

6. In a device for storing a hose and its nozzle within a building for accessibility and use from exteriorly of the building, an enclosure within the building for receiving and retaining the major portion of the hose, a valved water connection within the building for attachment of the hose thereto, an outlet comprising a box portion for insertion into the building wall with one box surface substantially in the plane of the exterior wall surface and a tubular casing portion having a plurality of separate passages therethrough, one casing passage providing for free movement of the hose therethrough and having an inwardly extending peripheral ridge for limiting movement of the nozzle therewith, and a rod extending through another casing passage for manual operation of the valve from outside the building.

7. In a device for storing a hose and its nozzle within a building for accessibility and use from exteriorly of the building, an enclosure within the building for receiving and retaining the major portion of the hose, a valved water connection within the building for attachment of the hose thereto, an outlet comprising a box portion for insertion into the building wall with one box surface substantially in the plane of the exterior wall surface and a tubular casing portion having a plurality of separate passages 55 therethrough, one casing passage providing for free movement of the hose therethrough and having an inwardly extending peripheral ridge intermediate the length thereof for limiting movement of the nozzle therewith, and a telescoping and universally jointed rod rotatably supported in and extending through another casing passage for manual operation of the valve from outside the building.

8. In a device for storing a hose and its nozzle within a building for accessibility and use from exteriorly of the building, an enclosure within the building for receiving and retaining the major portion of the hose, a valved water connection within the building for attachment of the hose thereto, an outlet comprising a box portion for insertion into the building wall with one box surface substantially in the plane of the exterior wall surface and a casing portion having a plurality of separate passages therethrough, one casing passage providing for free movement of the hose therethrough and having an inwardly extending peripheral ridge for limiting movement of the nozzle therewith, a rod extending through another casing passage for manual operation of the valve from outside the building, and rounded surfaced means rotatably mounted in the box for guiding movement of the hose from the casing and through the box.

9. In a device for storing a hose and its nozzle within a building for accessibility and use from exteriorly of the building, an enclosure within the building for receiving and retaining the major portion of the hose, a valved water connection within the building for attachment of the hose thereto, an outlet comprising a box portion for insertion into the building wall with one box surface substantially in the plane of the exterior wall surface and a casing portion formed by a tube within another tube and defining a plurality of separate passages through the casing portion, one casing passage providing for free movement of the hose therethrough and having an inwardly extending peripheral ridge for limiting movement of the nozzle therewith, a rod extending through another casing passage for manual operation of the valve from outside the building, and spaced rollers mounted in the box adjacent an end of and grooved to arcs on substantially the radius of the inner tube, the rollers being mounted on vertical axes for guiding movement of the hose from the casing and through the box.
